UNITED STATES PATENT OFFICE.

ELMER A. KLAPP, OF NEW YORK, N. Y.

DESIGN FOR A HERO-EMBLEM PIN OR BUTTON.

55,799.

Specification for Design.

Patented July 13, 1920.

Application filed March 4, 1918. Serial No. 220,402. Term of patent 3½ years.

To all whom it may concern:

Be it known that I, ELMER A. KLAPP, a citizen of the United States, residing at New York, in the county of New York and State of New York, have invented a new, original, and ornamental Design for a Hero-Emblem Pin or Button, of which the following is a specification, reference being had to the accompanying drawings, forming part thereof.

The figure is a plan view of a pin showing my new design.

The design shown includes red and blue

stripes over-laid with a five pointed star in white, the three colors constituting the national colors, and the whole being surrounded by a black band or border indicating mourning for the lost hero.

I claim:

The ornamental design for a hero emblem pin or button as shown.

ELMER A. KLAPP.
